UNITED STATES PATENT OFFICE.

LINDSAY C. PRITNER AND HENRY C. DORRIS, OF JOHNSTOWN, PENNSYLVANIA.

MAKING SIDE FRAMES.

Application filed August 15, 1922. Serial No. 581,929.

To all whom it may concern:

Be it known that we, LINDSAY C. PRITNER and HENRY C. DORRIS, citizens of the United States, and residing in the city of Johnstown, county of Cambria, and State of Pennsylvania, have invented certain new and useful Improvements in Making Side Frames; and we do hereby declare the following to be a full, clear, and exact description of the invention, such as will enable others skilled in the art to which it appertains to make and use the same.

Our invention relates to making side frames with particular reference to side frames for railway trucks formed of pressed steel, and has for its object to materially simplify the fabrication of such side frames from single sheets of steel, with certain ancillary reinforcements and additions, involving the cutting of a blank of a shape or contour generally corresponding to the two lateral faces of the side frame, with appropriate openings to define the top and bottom arch bars, to receive the bolsters and column guides, to provide integral pedestal tie bars, and for other specific purposes hereinafter described, die flanging certain of the marginal edges of the blank and of the openings therein, bending the blank transversely of its longitudinal axis to bring the two halves thereof into parallelism, with the marginal flanges in abutting relation, welding the abutting flanges together, and finally welding the additions and reinforcing elements in place.

The invention is illustrated in the accompanying drawings, in which:

Figure 1 is a plan view of a rectangular plate from which the blank for a pressed metal truck side frame is formed; Figure 2 is a plan view of the cut blank from which the pressed metal shape for the truck side frame is made; Figure 3 is a central vertical longitudinal sectional elevation through the blank after it has been flanged; Figure 4 is a vertical sectional elevation through the bending dies, the partially formed pressed metal truck side frame being shown in end elevation therein at the end of the bending operation; Figure 5 is an end elevation of the pressed metal truck side frame after the blank has been bent into its final form, but before the flanges have been welded together; Figure 6 is a side elevation of the finished truck side frame after it has been

welded; Figure 7 is an end elevation of the finished truck side frame shown in Figure 6; Figure 8 is a vertical transverse sectional elevation through the finished truck side frame, the section being taken on the line VIII—VIII of Figure 6; Figure 9 is a bottom plan view of the finished truck side frame; Figure 10 is a side elevation showing the end portions of the top and bottom flanging dies and a portion of the blank with the end of the pedestal tie bar bent down in the position it assumes before the flanging operation, and Figure 11 is a top plan view of the end portion of the bottom flanging die just after the flanging operation.

Referring now to the characters of reference on the drawings:—1 indicates the plain rectangular plate from which the blank is to be cut; 2 indicates generally the plate after it has been cut to form the blank; 3 are triangular shaped holes with rounded corners between the bolster openings and the ends; 4 are the bolster openings in the blank; 5 are openings between the pedestal tie bars and the inclined portion of the bottom arch bar and the end portions of the top arch bar; 6 are holes in the central portion of the top arch bar through which the interior journal box bolts are inserted; 7 are holes for welding the reinforcements near the ends of the top arch bar; 8 are the cut-out portions of the ends of the top arch bar which allow the ready insertion of the outer journal box bolts and also lighten the frame without lessening its strength; 9 are the outer flat ends of the tie bars of the cut-out blank; 10 are ears or added extensions to the tie bars to serve in holding the parts in position while their inner ends are flanged and outer ends bent as heretofore described; 11 are semi-circular holes in the ends of the tie bars and in the ends of the top arch bar member, which, when the parts are bent in their final position, form substantially circular holes for the journal box bolts; 12 are projecting portions of the flanges which are adapted to be welded together after the frame is pressed into its final shape; 13 are recesses or indentations between the projections 12 which form portions which are not to be welded; 14 are the bottom flanged edges of the blank and 15 are the bent ends of the pedestal tie bars after the blank has been flanged. The internal flanges of the triangular shaped holes 3 are 16, and the in-

ternal flanges of the top arch bar member over the bolster openings are 17, and the upper part of the top arch bar member is 18. The complete finished truck side frame 6 is generally indicated as 19 and the finished pedestal tie bar extension portions thereof are 20. The bottom pads 21 of these bars are welded in position, and these pads have central holes therein which register with 10 corresponding holes in the pedestal tie bars to receive the lower ends of the journal box bolts. The bolster guide pads are 22 and these are welded to the truck frame columns by their edges to maintain them in the locations shown. A reinforcing member 23 of channel section with trapezoidal flanges is neatly fitted within each end of the top arch bar member and welded thereto at the places indicated as 24, including the holes in the 15 sides of the top arch bar member as illustrated. 25 are the welds of the flanges which are thus joined. The holes through which the journal box bolts pass are 26. The former previously referred to for use in 20 shaping the top arch bar member is 27 and this is preferably composed of two wedge-shaped pieces, which, on account of their shape, may be readily withdrawn as desired. As illustrated particularly in Figures 10 and 30 28 is a part of the bottom flanging die having an inclined end portion 29 and an inclined inner side 30, while 31 is a portion of the top flanging die co-operating therewith. 32 is a part of the stripper plate 35 used in connection with the top and bottom flanging dies to assist in forming and holding the pedestal tie bar and in the ejection thereof from the bottom die after the flanging has been completed. The top bending 40 die is 36, which is secured in the groove 34 of the holder 33 by means of the bolts 35, while 37 is the bottom bending die provided with the bending groove 38 therein.

The operation of making a side frame 45 is as follows:—A blank rectangular plate 1 is placed upon a pair of cutting dies and at either one or two operations is cut to the form illustrated in Figure 2. After this the cut blank is preferably heated and placed 50 on a pair of flanging dies and flanged to the form shown in Figure 3. It is then preferably, at the same heat, placed over a bottom bending die 37 in the position shown by dotted lines in Figure 4, and then by the 55 action of the groove 38 in the bottom bending die and the downward movement of the bending die 36, which has the removable former 27 secured to the bottom edge thereof, is bent to the shape illustrated by full lines 60 in Figure 4. The former 27 is then withdrawn, or if desired, may be left in temporarily, and the partially bent shape is then placed between a pair of pressing dies and two halves are closed together to the 65 shape shown in Figure 5. After this is done

the adjacent contiguous edges of the projections of the flanges are welded together either electrically or otherwise. Reinforcing plates 23 are forcibly pressed into position and welded in the locations shown by 70 the dotted lines in Figure 6. The pedestal tie bar pads 21 are also welded in the positions indicated in Figures 6 and 9, the welding of these being accomplished around their edges. As particularly illustrated in 75 Figures 10 and 11, the integral projecting portions 10 of the tie bar are so shaped and located as to contact with the flanging dies and hold this part in such a way that the flanging of the inner portion of the tie bar is accomplished, and the shape of the dies is also such that the outer portions 20 of the pedestal tie bars is bent at right angles to the body portion of the frame and substantially parallel to and spaced the proper distance from the extending ends of the bottom portion of the top arch bar so as to receive the journal boxes (not shown) therebetween.

Although we have shown and described our invention in considerable detail, we do not wish to be limited to the exact and specific details thereof, as shown and described, but may use such modifications, in substitutions for, or equivalent thereof as are embraced within the scope of our invention, or as pointed out in the claims.

Having thus described our invention, what we claim and desire to secure by Letters Patent is:

1. The steps in the method of forming a 100 pressed metal side frame, which consists in taking a plain plate, simultaneously cutting the margins thereof and the openings therein, then die forming flanges around the margins of certain portions of said plate and certain of the openings therein, then bending said plate about its intermediate portion in such a way as to place the flanges of the two halves substantially opposite each other, and welding the halves together at 105 the flanges.

2. The steps in the method of forming a 110 pressed metal truck side frame, which consists in taking a plain plate, simultaneously cutting the margins thereof and the holes therein of one-half thereof at one operation, then turning the plate around and similarly cutting the other half, then forming flanges around certain of the plate margins and certain of the openings, then bending the plate about its intermediate portion until the flanges are adjacent, welding the adjacent edges of the flanges together; said flanges having previously been cut with indentations and projecting portions, which when the plate is bent are at certain and predetermined distances apart.

3. The steps in the method of forming a 115 pressed metal truck side frame, which consists in taking a plain plate, simultaneously

5 cutting the margins thereof and holes therein of one half of the plate at one operation, then turning the plate around and similarly cutting the other half, then die forming flanges around certain of the plate margins and some of the openings, then bending the plate about its intermediate portion until the flanges are adjacent, said flanges having previously been cut with indentations and 10 projecting portions, which when the plate is bent are at certain and predetermined distances apart, and then welding together the contiguous projecting parts.

15 4. The steps in forming a pressed metal truck side frame, which consists in cutting a plate to the outlines desired, including the various openings therein and providing extra extending portions of the pedestal tie bar members thereof, then flanging the plate 20 in a pair of flanging dies adapted to flange certain of the plate margins and the material around the various openings, said flanging dies being provided with portions adapted to contact with the extending portions 25 aforesaid to flange the inner portions of the pedestal tie bars while turning the outer flat ends thereof at about right angles to the body of the truck frame, bending the plate about its intermediate portion until the 30 flanges are adjacent, and welding the adjacent edges of the flanges together.

35 5. The steps in making a pressed metal truck side frame of integral form, consisting in cutting a plain plate to the shape desired with portions which are ultimately to form certain flanges provided with projections, then flanging various portions thereof including those provided with the projections aforesaid, then bending the plate about 40 its intermediate portion and placing the projecting portions of each half of the plate opposite each other, and then welding said projections together.

45 6. The steps in the method of forming a pressed metal truck side frame, which consists in cutting a plain plate to the shape desired, then die forming certain of the margins thereof and of the openings therein, then die bending the plate about its intermediate portion with the aid of a former adapted to contact with said intermediate portion and assist in shaping the top arch bar portion thereof, then withdrawing said former and closing the two halves until the 50 flanges are opposite and at certain predeter-

mined distances apart, and welding the adjacent edges of the flanges together.

7. The steps in the method of forming a metal truck side frame, which consists in cutting a plate around its margins and to 60 form various openings therein, certain of the margins being provided with projecting portions symmetrically arranged, then die flanging certain of the margins of said plate and the openings thereof, then bending the 65 plate about its intermediate portion and pressing the two halves toward each other in such a way that the projecting portions are opposite each other and spaced apart, and then welding together said projections. 70

8. The steps in the method of forming a truck side frame, which consists in cutting a plain plate around the margins thereof and to form bolster openings, side openings and end openings therein, while providing 75 projections on certain of the edges thereof and semi-circular openings in other portions, all symmetrically arranged, then die flanging certain of the margins, then bending the plate about its intermediate portion and 80 pressing the two halves together, whereby the projections are opposite each other and spaced apart and the semi-circular openings are opposite each other and adapted to form substantially circular holes in the finished frame, and then welding the projections together. 85

9. The method of forming a pressed metal frame, which consists in cutting a plain plate around the margins thereof and with 90 various openings therein and simultaneously providing projecting portions on various margins symmetrically arranged, then die flanging certain of the margins, then bending the plate about its intermediate portions 95 with the aid of a former adapted to assist in shaping the interior of the top arch bar member, then withdrawing said former and pressing the two halves toward each other, then welding the contiguous edges of said 100 projections, then introducing flanged reinforcing members in the ends of the arch bar portion and welding same in place, and welding pads on the column portions to secure the same together, and to form bolster 105 guides.

In witness whereof we hereunto affix our signatures.

LINDSAY C. PRITNER.
HENRY C. DORRIS.
